UNITED STATES PATENT OFFICE.

ALBERT DREYER, OF LUZERNE, SWITZERLAND.

HONING AND STROPPING APPARATUS FOR TWO-EDGED RAZOR BLADES.

Application filed July 9, 1923. Serial No. 650,496.

To all whom it may concern:

Be it known that I, ALBERT DREYER, manufacturer, a citizen of Switzerland, residing at Lucerne, Switzerland, have invented certain new and useful Improvements in Honing and Stropping Apparatus for Two-Edged Razor Blades; and I do hereby declare that the following is a full, clear, and exact description of the invention, such as will enable others skilled in the art to which it appertains to make and use the same.

My invention relates to a device for honing and stropping double-edged safety razor blades and is distinguished by the features that a blade holder which can swing around a stationary axle supported in a frame-like casing is arranged between two honing or stropping bodies which are shiftable in said casing in opposite directions and transversely with respect to the blade and in mutual dependency, and that said holder is positively connected with these bodies in such a manner that both faces of each cutting edge of the blade are honed or stropped whilst the said bodies are reciprocated, the blade holder being suitably oscillated, as more fully described hereinafter in connection with the drawings. Means are provided to regulate in a simple manner the grinding pressure according to the requirement whilst the grinding proceeds.

Two constructional examples of my improved razor blade sharpening device are illustrated in the accompanying drawing in which Figure 1 is a plan thereof, partly in horizontal section; Figure 2 is a longitudinal section on line A—A of Figure 1; Figure 3 is another such section on line B—B thereof; Figure 4 is a cross section drawn on a larger scale; Figure 5 is a side view of the blade-carrier; Figure 6 is a plan of the second example, partly in horizontal section; Figure 7 is a longitudinal section on line A'—A' of Figure 6; Figure 8 is another such section on line B'—B' also of Figure 6; Figure 9 is a third longitudinal section through Figure 6, on line C—C thereof; Figures 10, 11 and 12 are details which are fully dealt with hereinafter.

Referring to Figures 1—5, the casing is composed of the two longitudinal members *a a* which are channel-shaped in cross sec-

tion (Fig. 4), and of the two frontal or end members *b b* which are connected with the frame members *a a* by screws, rivets, or in any other suitable manner.

The open sides of the frame members *a a* which face each other are partly closed by flat bars *d d* extending longitudinally through said members and being spaced at their upper and lower edge from the adjacent horizontal parts of the said members so as to form guide passages for lugs *f f* firmly connected with two slides *e e'*, of which one is at the top of the frame or casing the other at the bottom thereof, but which are shorter than the frame or casing (Figs. 2 and 4). These slides are guided also at the opposite surfaces by flanges *e³* forming parts of the slides, the flanges of the upper slide extending downwards, those of the lower slide being directed upwards, as illustrated in Figure 4.

The slides *e e'* serve as carriers for the honing or stropping bodies *h h'*, which are attached to plates *i i'* pressed against additional flanges *k k'* which project inwards from the flanges *e³* of said slides, the pressure being exerted by flat springs *j*, as shown in Figure 4. The honing and stropping bodies *h h'* can thus yield counter to the pressure of said springs.

The bodies *h h'* are connected with each other by two endless bands or cords or wires *m m* housed in the channels of the side members *a a* of the casing. Each band or cord or wire runs over three rolls *n¹ n²* and a roll *o* which latter is secured to the axle *p¹* of the blade carrier *p*. The roll *n¹* on either side is located between the blade holder roll *o* and the roll *n²*. Each cord or wire *m* is connected with the slides *e e'* by lugs *m'* where there are inserted coiled springs *r* holding the cord or wire tight. Referring to Figure 3, the wire *m* is, practically, divided into a short piece and a long one, the short piece commencing at the upper lug *m'* (lefthand end of the figure), running over the roll *n* and terminating at the lower lug *m'* (righthand end of the figure); the long wire piece commences at this latter lug, runs over the adjacent roll *n¹*, back to the centre roll *o* over which it passes in the contrary direction, then to the righthand roll *n²*, the wire parts between the roll *o*

and the roll n^1 crossing, each other, as shown in Figure 4. The wire then runs over the righthand roll n^2 and gets finally back to the lug m' at the lefthand end of the 5 casing.

The blade holder which is a flat member as shown in the centre part of Figure 2 (in cross section) is provided with some hook-like pins s' intended to extend through the 10 known apertures s^2 of the blade s .

The manner of operation of the device is as follows:

The slide e which is provided with a projecting part e^2 forming a grip is shifted in 15 the direction indicated by the arrow 1 to the right, and simultaneously therewith the slide e' is shifted in the direction indicated by the arrow 2 to the left, the slide e' being moved in this direction by the slide e by 20 reason of the connection of the slides by the wire parts and the rolls, as above described. But when the shifting commences, also the roll o is rotated, and consequently 25 the blade holder p with the blade s are turned, viz., from the position I shown in Figure 2 in dotted lines into the position II shown in this figure in full lines, the blade being so turned that the upper face of the lefthand cutting edge bears against the honing body h and the lower face of the right-hand edge bears against the honing body h' , as shown in full lines. The strength of this 30 pressure under which the honing is effected corresponds to the friction arising between the roll o and the piece of wire etc. gliding along over or around it and the time of the honing procedure is determined by the duration of the motion of the honing bodies h h' , or of the slides e e' respectively, the 35 honing path in the respective direction being finished when each slide has arrived at the end of its guide way in the frame or casing. Having arrived in this position, the slides with the honing bodies are shifted 40 rearwards into their former position, viz., that shown in Figure 2, but at the commencement of this rearward motion, also the roll o is rotated, so that the blade is turned from the position shown in full lines 45 (Fig. 2) into that shown in dotted lines, in which the other two faces of the two edges are honed, as will now be clear without entering into further details.

The blade is honed by a sufficient number 50 of reciprocations of the slides with the honing bodies by means of the grip e^2 . Instead of honing bodies proper, that is to say, grinding bodies, stropping bodies may be employed which strop the already ground or 55 honed blade. The finished blade is removed from the holder p by shifting it off the hook-like pins p' so that these may pass through the apertures s^2 of the blade.

Instead of transmitting the motion from 60 one slide to the other, and to the blade holder

axle, by rolls and wires, racks and pinions may be employed as is the case in the modification illustrated in Figures 6-10.

The slides, the means for guiding them, the manner of supporting the honing or stropping bodies in the slides, all this is practically just so as in Figures 1-4. The same is true of the manner of, and means for, attaching the blade to the blade holder. 70

The blade holder axle forms at its ends 75 pivots p' which extend through the inner rails d and carry each a sleeve u having a flange u' . Each sleeve supports a pinion t' which is loosely rotatable thereon and meshes with another pinion t carried by a pivot x , Figs. 6 and 8. The axial length of the pinion t is greater than the axial length of the pinions t' , and each meshes with two racks y and y' which form parts of the slides e and e' , or are secured thereto respectively. It is obvious that the slide e' (with its honing or stropping body) can be reciprocated by reciprocating the slide e (with its honing or stropping body) by means of the grip e^2 , the motion of the slide e being transmitted to the slide e' by means of the pinions t which are driven by the racks y and drive the racks y' . The reciprocations are, however, transmitted also to the blade holder axle, for which purpose knob-like projections v are provided which are located in apertures of the longitudinal frame parts, a in the axial direction of the blade holder axle. Each knob v is attached 80 to a flat spring w by which it is pressed against the hub of the adjacent pinion t' which in its turn, is pressed against the flange u' of the sleeve u which, as has been described, is secured to the pivots of the blade holder axle. The rotation of the pinions t is, thus, transmitted to the blade holder with its blade under the friction produced by the springs w , of which there is, of course, one on either side of the apparatus. 85

The same friction determines the strength with which the blade faces are pressed against the honing or stropping bodies whilst these bodies are reciprocated. There are also in this case all four faces of the blade sharpened, exactly as already described in connection with Figures 1-5.

Owing to the buttons v being accessible from the outer side of the apparatus, they may be pressed in the direction towards one another, i. e. against the cog-wheels t' , whereby the friction between the buttons and said wheels, as well as between these and the sleeve flanges u' , may be increased or decreased, and, consequently, also the pressure with which the blade faces are laid against the honing or stropping bodies may be varied or adjusted, as required or desired. 120

It has been found suitable to the purpose 125 to make the ends of the lateral rims of the 130

slides form lugs, as shown at k^2 in Figs. 2 and 5, in such a manner, that the cutting edges never contact with the additional flanges k k^1 ; the laterally curved rims or edges of the blade glide along said lugs k^2 whereby the cutting edges are prevented from contacting with the said rims or edges.

Instead of the slot d' of Figure 2 (provided for facilitating the insertion of the 10 blade to be sharpened), one of the longitudinal frame members b (Figs. 6, 7, 9 and 12) is provided with a plate d^2 having a semi-circular recess d^3 which receives one of the pivots p' of the blade carrier axle. 15 Owing to the plate d^2 being made oblique in the manner illustrated in Figures 10 and 12, it is rendered possible to shift the blade on its holder in order to attach it thereto and detach it therefrom, and, besides, the 20 blade is prevented from unintentional shifting during the honing or stropping by the inwardly directed wall of the plate.

The honing or stropping bodies may also be made in the manner shown in Figure 11, 25 in which each body consists of a grinding

or honing part h^3 and of a stropping part h^2 , the blade being, thus, acted on by both parts consecutively, as well as alternately, whilst said bodies are reciprocated.

I claim:

A honing and stropping device for double edge razor blades comprising a frame consisting of a pair of channel-shaped side members, a blade holder journalled within said side members, a pair of hone supporting bodies, lugs carried by said bodies and guided within said channel-shaped side members, means arranged within said channel-shaped side members for operatively connecting said hone supporting bodies and blade holder whereby upon longitudinal movement of said hone supporting bodies, said blade holder will be caused to oscillate therebetween, and the opposite edges of the blade carried by the holder will be simultaneously and alternately honed.

In witness whereof I have hereunto set my hand.

ALBERT DREYER.
